UNITED STATES PATENT OFFICE.

ARTHUR E. HALLADAY, OF WAYNE, NEBRASKA.

SPIKE.

1,120,934.

Specification of Letters Patent. Patented Dec. 15, 1914.

Application filed May 15, 1914. Serial No. 838,782.

To all whom it may concern:

Be it known that I, ARTHUR E. HALLADAY, a citizen of the United States, residing at Wayne, in the county of Wayne and State 5 of Nebraska, have invented certain new and useful Improvements in Spikes, of which the following is a specification.

This invention relates to an improved spike and the principal object of the invention is to provide an improved means for locking the spike in a tie, the spike being provided with a tapered pin receiving pocket in which a pin may be placed to spread the arms of the spike and lock the spike.

Another object of the invention is to so construct the pocket that the securing pin may be easily driven into place after the spike has been driven into the tie.

20 This invention is illustrated in the accompanying drawings, wherein—

Figure 1 is a rear elevation of the spike before the securing pin is inserted; Fig. 2 is a view similar to Fig. 1 with the securing pin inserted; Fig. 3 is a vertical sectional view through the spike taken along the line 3—3 in Fig. 2 with the securing pin in place and shown in elevation; and Fig. 4 is a transverse sectional view taken along the 30 line 4—4 of Fig. 1.

The spike 10 is split longitudinally to form the arms 11 which are provided with teeth 12 and have their lower end portions 13 tapered to form a penetrating point for 35 the spike. Grooves are formed in the arms 11 thus forming a pocket 14 which tapers toward the penetrating end of the spike. It should be noted that by providing a groove instead of a slot a wall will be provided at 40 the inner end of the pocket.

After the spike has been driven into the tie to such an extent that the head 15 engages the rail base, the spreading finger or wedge 16 is inserted in the pocket 14 and driven down into the same so that the arms 11 will be spread to the position shown in Fig. 2. It should be noted that the lower end 17 of this wedge is rounded so that the wedge may be placed in the pocket at an 45 incline and then easily driven downwardly

to the position shown in Fig. 3. A head 18 is provided to permit the wedge to be easily driven into place. It should be noted that by having the spike formed of resilient material that a binding action is caused 55 which will hold the wedge in place and prevent the lower end of the wedge from slipping out of the pocket 14 when driving the wedge downwardly. If it is desired to remove the spike, the head 18 may be engaged 60 by a suitable moving tool and the wedge withdrawn from the pocket. The spike can then be removed by a suitable moving tool.

What is claimed is:—

1. A spike provided with a longitudinally 65 extending slot forming arms having their lower end portions tapered to form a penetrating point and also provided with gripping teeth, said arms having their adjoining edge portions provided with grooves extending longitudinally of the arms and forming a tapered pocket terminating short of the penetrating point and head of the spike, and a spreading wedge fitting into said pocket and having its lower end portions curved to 70 form a guiding surface and its upper end portion provided with a head. 75

2. A spike provided with a longitudinally extending slot forming arms, said arms having their rear faces cut out to form a tapered pocket in said spike having an inner wall, and a spreading wedge for fitting in 80 said pocket and spreading said arms, one end of said wedge being rounded and the opposite end being provided with a head. 85

3. A spike provided with longitudinally extending arms cut out to form a longitudinally extending pocket leading from one face of the spike, and a spreading wedge for fitting in said pocket to spread said arms, the 90 inner wall of said pocket adapted to guide the movement of said wedge when passing into the pocket.

In testimony whereof I affix my signature in presence of two witnesses.

ARTHUR E. HALLADAY.
